UNITED STATES PATENT OFFICE.

HENRY D. WASHBURN, OF BOSTON, MASSACHUSETTS.

MACHINE FOR OPENING CANS.

Application filed January 19, 1923. Serial No. 613,745.

To all whom it may concern:

Be it known that I, HENRY D. WASHBURN, a subject of the King of Great Britain, and a resident of Boston, in the county of Suffolk and Commonwealth of Massachusetts, have invented certain new and useful Improvements in Machines for Opening Cans, of which the following is a specification.

This invention relates to a machine for opening cans that is particularly adapted for household, club, and hotel use, or wherever canned foods and goods are extensively used.

An object of the invention is to produce a simple and inexpensive machine which may be rapidly operated to entirely remove the cover or end of a can, such as food stuffs are packed in, by a cutting process.

It is a further object of the invention to produce a can opening machine that is capable of operating upon cans of various sizes, and which is so constructed that the usual manual adjustments necessary to accommodate the changes from one sized can to another are in the main eliminated.

Another object of the invention is to produce a can opening machine wherein a can of any size, within the limits of the machine, may be placed therein and automatically centered, clamped, and punctured, and thereafter by a single rotary movement of the cutting tool remove the top end thereof.

It is also an object of the invention to produce a machine of this class wherein a single movement of the operator will suffice to unclamp the can and simultaneously reset the table and clamp for the next operation.

A further object of the invention is to produce a machine of this class wherein the cutting member is comparatively loosely mounted therein, and slideable by hand instantly in the desired direction to accommodate the size can to be opened.

A still further object of the invention is to produce a can opening machine wherein a minimum of manual operations has been attained to rapidly and efficiently open a can, and wherein the can and its support are stationary during the opening operation.

and wherein the cutting tool is the only portion of the machine which requires especial adjustment when the cans vary in size.

To the attainment of the above objects the invention further consists in certain novel features of construction and arrangement of parts which will be fully understood from a description of the drawings and the claims hereinafter given.

Of the drawings:

Figure 1 represents in front elevation one form of can opening machine embodying the invention.

Figure 2 a view looking toward the left Figure 1.

Figure 3 a section on the line 3—3 Figure 1.

Figure 4 a detailed view of the cutting tool carrying arm showing the cutting tool and means to cause adjustment thereof.

Figure 5 a section on the line 5—5 Figure 4.

Figure 6 is a diagrammatic plan view of a portion of a can top indicating the preferred arrangement of the cutting tool.

Figure 7 a section on the line 7—7 Figure 6.

Like characters designate like parts throughout the several figures of the drawings.

Referring to the drawings: The drawings herewith illustrate a convenient form of can opening machine to describe the present invention, but it will be understood that it is not the intention to limit the invention to the precise construction and arrangement shown as it is obvious that various changes might be made therein without departing from its spirit and scope.

The present machine is shown as being supported on a table or shelf 10 by means of the feet 11 rearwardly extending from and forming part of a bracket 12, which has the bosses 13 at each side thereof, see Figures 1 and 2, in which the rods 14 are guided in holes provided therefor.

At their upper ends the rods 14 are joined by and fast with a yoke 15 having the boss 16 through which passes a spindle 17 forming part of the hand lever 18 and to which

the cutting tool carrying member 19 is pinned or otherwise secured.

From the foregoing it will be readily understood that the hand lever 18 may be 5 revolved about the axis of the spindle 17 and in so doing cause the member 19 to revolve likewise.

It will also be understood that the yoke 15 and the parts attached thereto may be 10 raised and lowered by reason of the sliding fit of the guide rods 14 in the holes of the bosses 13.

The rods 14 and yoke 15 form a frame which may be impositively locked in elevated position by means of the springs 40 15 engaging the notches 41 of the rods 14 see Figure 1.

The bracket 12 is provided centrally thereof with a boss 20 through which loosely 20 passes the spindle or stud 21 fast with the can receiving table 22 built somewhat in the form of a cross, the side extensions of which are bifurcated as at 23 to straddle the rods 14 and thereby restrain the table 25 22 from the tendency to revolve during the can opening operation and yet permit the said table to move vertically.

The bosses 13 are so arranged as to accommodate the pivot pins 24 to each of which is 30 fast at each end thereof a bell crank clamp lever 25, the upper end of each of which has a clamp shoe 26 pivoted thereto, while the lower or inner end engages the hub 27 of the table 22.

35 Springs 28 loosely surround the pins 24, each having an end fast with the bracket 12, and an end engaging its respective bell crank clamp lever as clearly shown in Figures 1 and 2.

40 Normally the clamp levers 25 will occupy approximately the position indicated by dotted lines in Figure 1, with the collars 29 of the rods 14 resting on the table 22, which protects the cutting tool and punch from 45 contact with the table.

To use the machine, the operator will 50 grasp the hand lever 18 and raise the yoke 15 sufficiently high to place a can on the supporting table 22, centering it as near as the eye will permit, and thereafter a downward 55 thrust of the can either by hand or through lever 18 and yoke 15 will cause the table 22 to descend and force the clamp levers 25 inwardly to contact with and center the can for the correct position to begin the cutting 55 operation.

The yoke 15 will now be further thrust 60 downwardly through the grasp of the operator on the lever 18, which action causes the table to descend until the shoes 26 complete the centering of the can and clamp it and the center punch 30 and the cutting tool 31 to penetrate the end of the can and brings the stop 32 of the member 19 in contact with 65 the top edge of the can which stop 32 per-

forms the function of a top clamp for the can and which may be revolved while acting as a clamp.

So far as the cutting tool 31 is concerned the cutting operation may now proceed, but 70 it is advisable to guard against rotary movement of the can during the cutting thereof, and, therefore further downward pressure will be given the lever 18 to cause the clamp shoes 26 to firmly grip the can, and prevent 75 such movement. While depressed, the said lever will be given a complete rotation which will make a cut around the can approximately parallel to the periphery thereof, and preferably close thereto, and will cause a 80 circular disk to be cut from the can top.

Pressure on the lever 18 will now be removed and an upward pull thereon will raise the cutting tool 31 and punch 30 which are at this time in close engagement with the cut out disk carrying it with them and freeing it from the can. Simultaneously with this movement the clamp levers will release the can so that it may be removed from the table 22, when the table and clamp levers will assume approximately the dotted line positions thereof shown in Figure 1.

If desired a friction pad 35 such as emery cloth or the like may be used to aid in preventing rotary movement to the can during 35 the cutting operation.

A feature of the invention consists in mounting the cutting tool so that it may be instantly moved to the desired position for cutting.

Heretofore the cutting tool has been so mounted as to require considerable attention to adjust it to the proper position.

In the present instance the tool is preferably L shaped, as seen in Figure 4, and is secured to a block 36 by means of screws 37.

The said block 36 has a running fit in the guideway 38 formed in the member 19 and has an upwardly extending finger piece 39 to aid in sliding it in the desired direction.

It will be understood that normally the screws 37 are set up just enough to retain the tool and block in working condition and permit freedom of movement longitudinally of the member 19, but if need be, they may be 115 set up to frictionally hold said tool and block in a given position.

Another feature of the invention consists in the arrangement of the cutting tool, which enables a clean cut to be made close up to 120 the inner surface of the wall of the can, at which location a cleaner cut can be made than at any other part of the can top nearer the center.

To accomplish this, the cutting tool 31 will 125 preferably be set as indicated in Figure 6 wherein the dotted line A represents the median line of the member 19.

Assuming that the direction of cutting movement is as indicated by the arrow, the 130

tendency of the cutting tool to hug the inner wall will be evident, even though the start of the cut was made inside therefrom.

By this arrangement, the objectionable ragged and burred cut usually obtained, is greatly eliminated, as the passage of the tool tends to, and in fact does, to great extent, press the cut edge of the attached top snugly against the inner surface of the wall of the can thus greatly facilitating in the subsequent pouring of the contents therefrom, as well as reducing the danger of cutting the fingers while handling the can.

Having described the invention I claim:

1. A can opening machine comprising a stationary support; a frame vertically movable in said support; a nonrotatable table adapted to move vertically in said support and adapted to receive a can thereon through which movement is imparted to said table by said frame; means to center a can on said table upon vertical movement of said table; said means also normally retaining said table yieldingly in raised position; and means carried by said frame adapted to effect an opening in a can.

2. A can opening machine comprising a stationary support; a frame vertically movable in said support; a nonrotatable table vertically movable in said support and adapted to be moved by said frame through the medium of a can placed on said table; means carried by said frame adapted to effect an opening in a can placed on said table; and means controlled by downward movement of said table and adapted to clamp a can thereon against rotary movement during the opening of a can.

3. A can opening machine comprising a stationary support; a frame vertically movable in said support and adapted to cause movement to a table when a can is mounted thereon; a cutting tool mounted on said frame and rotatable relatively thereto; a nonrotatable table carried by said support and vertically movable relatively thereto and adapted to receive a can; and means under the control of said table to centrally position a can placed thereon and thereafter clamp said can against rotary movement during the operation of said cutting tool.

4. A can opening machine comprising a stationary support; a yoke shaped frame slidable in said support; a nonrotatable table yieldingly mounted in said support; means coacting with said table to first position and then clamp a can on said table; and a rotatable cutting tool mounted on said frame adapted to effect an opening in a can.

5. A can opening machine comprising a stationary support; a yoke shaped frame slidable in said support and adapted to be held in elevated position by locking means for said frame; a nonrotatable table yieldingly mounted in said support; means co-

acting with the movement of said table to first position and then clamp a can thereon, a rotatable cutting tool mounted on said frame and adapted to effect an opening in a can; and a lever adapted to actuate said cutting tool.

6. A can opening machine comprising a stationary support; a frame movable relatively to said support said frame having means to lock it in a given position; a non-rotatable table yieldingly mounted in said support and adapted to be moved relatively to said frame; clamp levers mounted on said support and adapted to coact with said table to first position and then clamp a can on said table; means to yieldingly retain said table and levers in normal position; a cutting tool mounted on said frame; and means to actuate said cutting tool.

7. A can opening machine comprising a stationary support; a frame movable relatively to said support consisting of two guide rods connected at their upper end by a yoke; a cutting tool carrier revolvably mounted in said yoke; a lever adapted to actuate said carrier; means coacting with said rods to lock said frame in a given position; a cutting tool slidably mounted in said carrier; a nonrotatable table adapted to move relatively to and with said frame; means to position and clamp a can on said table; and means to yieldingly support said table.

8. A can opening machine comprising a support; a nonrotatable table adapted to receive a can to be opened; means coacting with said table adapted to first center and then clamp a can thereon; and means actuated by the vertical movement of said table for operating said centering and clamping means, and means to effect an opening in a can.

9. A can opening machine comprising a support; a nonrotatable table movably mounted in said support; a frame movably mounted in said support and movable relatively to said table and movable with said table; means carried by said support and adapted to coact with said table to first center and then clamp a can against lateral movement on said table upon movement of said table, said means including clamp members; means to normally retain said clamp members in can receiving position; and means to effect an opening in a can.

10. A can opening machine comprising a support; a nonrotatable table adapted to receive a can and movably mounted in said support; a frame movably mounted in said support and movable with and relatively to said table; means carried by said frame adapted to clamp a can to said table; clamp members pivotally mounted on said support and adapted to coact with said table to clamp a can thereon upon clamping move-

ment of said first clamping means; means to normally retain said clamp members and consequently said table in can receiving position; and means to effect an opening in a can.

11. A can opening machine comprising a support; a frame movable in said support; a table adapted to be guided by said frame and movable in said support; means carried by said frame to clamp a can to said table;

means carried by said support and coacting with said table to further clamp a can thereon; frictional means on said table adapted to prevent rotary movement of a can during the cutting operation; and means to effect an opening in a can. 15

Signed by me at Boston, Massachusetts, this 18th day of January, 1923.

HENRY D. WASHBURN.
